UNITED STATES PATENT OFFICE.

HERBERT H. STEELE, OF MARCELLUS, NEW YORK, ASSIGNOR TO THE MONARCH TYPE-WRITER COMPANY, OF SYRACUSE, NEW YORK, A CORPORATION OF NEW YORK.

TYPE-WRITING MACHINE.

1,138,992.

Specification of Letters Patent. Patented May 11, 1915.

Application filed February 24, 1913. Serial No. 750,278.

To all whom it may concern:

Be it known that I, HERBERT H. STEELE, citizen of the United States, and resident of Marcellus, in the county of Onondaga and State of New York, have invented certain new and useful Improvements in Type-Writing Machines, of which the following is a specification.

My invention relates to platens and paper feeding mechanism for typewriting machines and its object generally is to provide improved means for controlling the parts of a divided or sectional platen and the work sheet or sheets fed thereover.

While the principles of my invention are applicable generally said invention relates specifically to improvements on the inventions shown in my Patents Nos. 1,052,021 and 1,052,186, both granted February 4, 20 1913.

In carrying out my present invention I provide, as before, for automatically unlocking that one of the platen sections which is normally locked against rotation and for concurrently coupling or connecting the two platen sections so that they may be turned or spaced equally together, but in the present instance I also provide in addition for varying the connection between the two platen sections as for example by shiftable gear mechanism so as to vary the relative extents of simultaneous movement and the relative rates of speed of said sections. By so doing it is possible to turn the platen section on which the record sheet is fed to a less extent and at a slower rate than the other section so as to obtain a greater condensation of the record entries. Further, means are provided by the present invention for rendering inoperative at will the platen lock of the prior construction and for concurrently coupling the sections together so that at a line spacing operation they may in all positions of the carriage be turned together and at the same rate of speed, thus providing for their unrestricted use as a single unitary platen.

To the above and other ends my invention consists in the features of construction, combinations of devices and arrangements of parts hereinafter described and particularly pointed out in the claims.

In the accompanying drawings, Figure 1 is a fragmentary side elevation of the upper 55 part of a Monarch typewriting machine

embodiment my invention. Figs. 2 and 3 are respectively a side- and front elevation partly in section of the improved coupling devices for variably connecting the parts of the sectional platen. Fig. 4 is a fragmentary vertical sectional view taken longitudinally of the platen through the axis thereof, said view showing also some of the associate parts. Fig. 5 is a perspective view showing the device or cam for actuating the platen 60 coupling devices.

As appears from Fig. 1, the main frame of the machine comprises posts 1 supporting a top plate 2 whence rise standards 3 to which are fixed grooved track-ways 4 co-operating through anti-friction balls 5 with a rear bar 6 of a platen carrier or carriage which further includes end bars 7 and 8. Said end bars provide bearings for a platen axle 9 on which are coaxially mounted end 70 to end the two parts or sections of a divided or sectional platen (Fig. 4). The left-hand platen or platen section 10 comprises a core 11 of wood and a sheath 12 of rubber composition and has operatively connected to its left-hand end a line spacing ratchet wheel 13. Coöperative with the ratchet wheel is a pawl 14 pivoted to an arm 15 which is supported loosely on a rock shaft 16 mounted on the end bar 7. Motion is communicated 75 to the rock shaft by the usual finger piece or line spacing handle 17 and is transmitted from a finger 18 on said shaft to the pawl 14 which is engaged by said finger. The usual spring mounted roller detent (not 80 shown) coöperates with the ratchet wheel 13. The pawl mechanism is comprised in the usual line spacing devices of the Monarch machine. Secured to the right-hand end of the platen section 10 as by wood screws 19 85 which screw into the core 11 is a platen head 20 provided with a long external hub 21 and a shorter internally extending hub 22. A cross pin 23 passing transversely through the hub 21 and axle 9 secures the platen 100 head 20 and the platen section 10 to said axle. The right-hand platen or platen section 24 is mounted to the right of the platen or section 10 and comprises a wooden core 25 and a sheath 26 of rubber composition. 105 The platen section 24 has secured to the left end of its core 25 by wood screws 27 a platen head 28 provided with an internal hub 29 which bears rotatably on the hub 21. It will be seen that the two platen heads 20 and 23 110

abut each other and one has a part on which the other is adapted to bear, thus providing for a suitable bearing in which any tendency to sag is minimized, this construction being substantially like that disclosed in my pending application, Serial No. 668,869, filed January 2, 1905. The two sheaths abut against each other at their inner ends, providing a practically continuous surface from one end to the other of the divided platen. A long collar 30 surrounding the shaft 9 abuts at its left-hand end against the hub 21 and extends rightward through an opening in the end bar 8, being secured to said end bar by a screw 31. Wood screws 32 secure a platen head 33 to the right-hand end of the platen section 24, said platen head being provided with an outwardly extending hub 34.

The devices for locking one of the platen sections against movement and for coupling or connecting the two platen sections to turn together comprise a gear wheel 35 having an inwardly extending hub 36 which bears on the collar 30 and in turn affords a support for the hub 34 which surrounds it. The gear wheel 35 is arranged inside the end bar 8 and rigidly secured to the right-hand platen section by a screw 37 which passes through the hub 34 and engages in a tapped opening in the hub 36. Outside the end bar 8 and abutting the end of the sleeve 30 is a second gear wheel 38 provided with a hub 39 formed with a groove 40 which cooperates with a short rib or spline 41 having inturned ends which are secured in holes in the shaft 9. Said spline is thereby fixed to the shaft 9 between the sleeve 30 and the hub 42 on the usual platen finger wheel 43. The gear wheel 38 is forced at all times to turn with the shaft 9 by reason of the spline connection therewith while said connection permits the gear wheel 38 to be slid along the shaft 9 and longitudinally thereof so as to vary its relationship therewith. The gear wheel 38 is of the same diameter as the gear wheel 35 and has the same number of teeth. Supported on the hub of the gear wheel 38 is a second and smaller gear wheel 44 having a fewer number of teeth. The gear wheel 44 has a hub 45 which is secured by a pin 46 in fixed relationship to the hub 39. Thus the pair of gear wheels 38 and 44 operate as a single member or two-part gear wheel. Detent devices are provided for maintaining a fixed relationship between the shaft 9 and the two-part gear wheel 38, 44, said detent devices permitting a relative adjustment of the parts so that such relationship may be varied and the operative gears changed. As appears from Figs. 2 and 4 these detent devices comprise a C-shaped spring 47 which partly surrounds the hub 39 near its outer end, one end of said spring being se-

cured to said hub by a headed screw 48. The other or free end of the spring projects outward providing a finger piece 47^a that is convenient for manipulation. Near its free end said spring has secured to it a locking pin 49 which fits slidably in a hole in the hub 39 and is adapted to engage with either of two holes or depressions 50 and 51 formed in the shaft 9. In Fig. 4 the locking pin is shown engaged with the hole or locking device 50 and thereby the position of the gears 38 and 44 lengthwise of the shaft 9 is maintained fixed. By lifting or pulling outward the free end 47^a of the spring or hand operated device 47, however, the pin 49 may be disengaged from the hole 50 so that the two-part or double gear 38, 44 is free to be slid outward along the shaft 9 until the pin 49 is opposite the hole 51. If now the spring be released the pin 49 will engage with the hole 51 to lock the two-part gear wheel in a new relationship lengthwise of the shaft 9. In either of these relationships the two-part gear wheel 38, 44 will at all times turn with the left-hand platen 10, the constant connection between the parts being made through the axle 9. The gear wheel 35, on the other hand, is connected through the screw 37 with the hub of the platen head 33 fast on the right-hand platen 24 so that said platen and said gear wheel 35 will always turn together.

The two platens are normally disconnected but means are provided for coupling or connecting them so that they will turn together, said means being movable independently of the two platens themselves and into and out of engagement with the gear wheels or coupling devices 35 and 38 or 44. The coupling means in the present instance comprise, as shown clearly in Figs. 3 and 4, a pinion 52 having an elongated hub 53 to the opposite end of which is staked by a pin 54 a pinion 55 having the same number of teeth and also contiguous to the pinion 55 a second and larger pinion 56, the pair of pinions 55 and 56 constituting a double or two-part pinion. The pinions 53, 55 and 56 are adapted to mesh respectively with the gear wheels 35, 38 and 44 although the two parts of the two-part pinion 55, 56 are never operative at the same time as will hereinafter appear. The elongated hub 53 is bored out and bears rotatably on the body portion of a shouldered screw 57, the left-hand end of which is supported on a rocking member or movable frame 58, the right-hand end of said screw being reduced and threaded and screwing into an angular extension 59 at the lower part of said rocking member. A nut 60 prevents displacement of said screw, said nut being threaded on to the reduced end thereof outside of the angular extension 59. The rocking member 110

or movable frame 58 is provided with a hub 61 which bears on a rod 62, said rod preferably being the rod or rock shaft which operates to release the feed rollers 5 ordinarily provided in the machine. A set of feed rollers, paper feeding or pressure devices 63 and 64 may be provided for co-operation with the platen section 10 and suitable paper feeding or pressure devices 10 may co-operate with the right-hand platen section 24.

If a continuous work sheet or strip is to be employed in connection with the right-hand platen section as in my Patent No. 1,052,021, then pressure devices such as 65 may be provided to draw such continuous sheet from the supply roll and feed it over said platen section. Such feed or pressure rollers for the two platen sections co-operate with other suitable devices, which may be of ordinary character including a paper table 67, for guiding and controlling the work sheet or sheets. The member or frame 58 has an upward and forward extension 25 or arm 68 which terminates in a tooth 69 that is laterally off-set into the plane of the gear wheel 35 and so that it may co-operate therewith. Said tooth is normally engaged with said gear wheel as shown in Fig. 1 30 and locks it and the right-hand platen section against rotation. At such times the member or gear device comprising the pinions 52, 55 and 56 is normally disengaged or inoperative, and to prevent accidental 35 turning of said member a spring detent 70 is provided, said member being bent at 71 at its lower free end to engage between the teeth of the pinion 52 at the back thereof as shown in Fig. 1. The upper end of the 40 detent 70 is bent forward and provided with a slot 72 which receives a screw 73 by which the detent is thus adjustably secured to the member or frame 58.

As shown in Fig. 1 the rear edge 74 of the rocking member 58 is normally substantially vertical, it being maintained in this position in any suitable way as for example by a spring 75 which as shown in Fig. 3 is coiled around the left-hand portion of the 45 hub 61, one end of said spring being secured to the member 58 and the other end being anchored or hooked around the shank of a headed screw 76 which engages in a collar 77 and secures the same in set relationship with the shaft 62. This spring 50 maintains the locking tooth 69 engaged with the gear wheel 35. When the lower end of the member or frame 58 is swung forward in the manner presently to be described, its 55 movement will be resisted by the spring 75 and after said member is released said spring will swing said lower end backward until the tooth 69 reengages with the gear wheel 35. The member 58 is held from leftward 60 movement lengthwise of the shaft 62 by the

collar 77 which co-operates with the left-hand end of the hub 61, while a second collar 78 fixed to the shaft 62 to the right of the member 58 will prevent rightward movement thereof along the shaft 62. The collars 77 and 78, however, permit the frame 58 to turn or move freely to limited extents on its support 62 under the action of the spring 75 and of an actuating device mounted on a stationary part of the machine in 75 order to unlock the right-hand platen section and couple it with the left-hand platen section. It is obvious that when the locking tooth 69 is in operation and the platen sections are disconnected a line spacing operation 80 of the finger piece 17 will be effective only on the left-hand platen section which will turn independently of the right-hand platen section, the latter remaining quiescent during line spacing operations of the 85 left-hand platen section so long as the lock 69 is effective and the two platen sections are disconnected. This will be the case, under the conditions heretofore described, so long as the left-hand platen section is within the 90 field of the types and the right-hand platen section is outside the printing field. In the present instance the actuating device aforesaid for effecting the unlocking of the right-hand section and the coupling thereof to the 95 left-hand section is in the form of a cam bar 79 which is arranged to intersect the path of the edge 74 of the locking member 58. Said cam bar as shown in Fig. 5 is 100 angular in cross section and is suitably secured as by screws 80 at its left-hand end portion to the top plate 2. Said bar, however, extends rightward beyond the top plate and its overhanging portion may be secured by a screw 81 to a bracket arm 82 rigidly 105 fixed to the lower track-way 4 by a screw 83. The right-hand end portion of the bar 79 is curved and bent rearward as indicated at 84 in order to intersect the path of the edge 74 and this curved portion is so located 110 that as the right-hand platen section approaches the printing point or the printing field of the types the edge 74 will engage with the stationary curved device or cam 84 with the result that as the leftward movement of the platen continues the edge 74 will be forced forward, swinging the member 58 on its axis. This swinging movement 115 disengages the tooth 69, unlocking the right-hand platen or section which it previously 120 had been prevented from turning during the operations of the line space handle or lever 17. Also such swinging movement carries the pinion 52 into mesh with the gear wheel 35 and assuming that the parts are arranged as in Fig. 4 will swing the pinion 56 into 125 mesh with the gear wheel 44. The pinion 55, it will be observed, is not at this time in the same plane as the gear wheel 38 but is to the right of said gear wheel and conse- 130

quently will not engage with said gear wheel when the member 58 swings forward.

As a result of the operation just described the platen or section 24 will be released from the locking or detent devices which normally prevent it from being turned and will be connected through the gear wheels 35 and 44 and their coöperating pinions with the left-hand platen section.

- 10 The parts are arranged so that the pinion 52 will partly engage with the gear 35 before said gear is entirely freed from the control of the locking tooth 69. The position of the parts following the described operation is illustrated in Fig. 2. The actuating device 79, 84 is arranged to effect the results described as the right-hand platen section enters the printing field, and it will be understood that during further leftward movement of the two-part platen said device or cam bar will operate to maintain the pinions engaged with their gears as illustrated in Fig. 2 so that a turning or line spacing movement communicated to the left-hand platen section from the regular line spacing devices will be participated in by the right-hand platen section. Owing, however, to the differential gear connections between the two platen sections the right-hand platen section will turn at a slower rate and to a less extent than will the left-hand section. In the present instance the parts are so proportioned and related that if a line space movement of two units be communicated to the left-hand platen section by operation of the finger piece 17 the corresponding movement of the right-hand section will amount to a little more than a single unit of line space movement. This 40 feature of my present invention enables it to be employed to advantage in various kinds of commercial typewriting such as railroad waybilling, or accounting, or the like, wherein a series of waybills or invoices are to be written and a record is to be kept of certain data from each bill. In such cases the waybills or bill sheets or invoices may be fed over the left-hand platen section while the record for each bill which includes all data that may be essential may be written in a single line on a record sheet fed over the right-hand section of the platen; said record sheet being if desired a continuous strip or web. By employing my present 50 invention in the manner described the lines on the right-hand or record sheet are spaced a little more than a single line space distance apart, although the line spacing devices including the pawl 14 and the finger piece 17 are set for double line spacing and such double line spacing or two units of line space movement will be communicated to the left-hand platen section at times when the right-hand platen section is receiving 60 slightly in excess of a single unit a line space

movement. It is desirable not to reduce the spacing on the waybills or bill sheets to less than two units for the reason that the bills are usually press copied and it is not feasible to make a good press copy when the spacing is closer than double line spacing. On the other hand, it is preferable not to reduce the line spacing on the record sheet quite to a single unit for the reason that in commercial typewriters where billing numerals are employed certain characters would overlap at their tops and bottoms.

If the nature of work is such, as is the case in some systems of commercial book-keeping, that it is desirable to feed or rotate the right-hand platen section uniformly with the left, it is only necessary as a preliminary to change or shift the pair of gears or two-part gear wheel 38, 44 to the right in the manner explained and to reset said two-part wheel or pair of gears by causing the pin 49 to engage with the hole 51. When thus reset the gear wheel 38 will be opposite to or in register with the pinion 55 while the gear wheel 44 will be out of register with or in a different fore and aft plane from the pinion 56. Consequently when the frame 58 is swung forward to couple the platen sections, movement will be communicated from the left-hand platen section to the right-hand platen section through a gear train comprising the gear wheel 38, the constantly connected pinions 55 and 52, and the gear wheel 35. As a result, the two platen sections will be spaced or advanced simultaneously and to uniform extents under a single actuation of the finger piece 17 when the right-hand platen section is in the printing field.

With the locking devices comprising the locking tooth 69 in operation it is not possible to rotate the right-hand platen section with the left-hand platen section under the adjustment of the parts last described except at times when the right-hand platen section is opposite the printing point, since at all other times the locking tooth 69 is in engagement with the gear wheel 35 and the right-hand section will remain quiescent. In some instances it may be desired to dispense at times with this locking feature and to arrange the rotary platens or platen sections so that they may be employed virtually as a single unitary rotary platen, thus enabling a wide sheet extending throughout the length of the two platen sections to be fed uniformly thereover at each actuation of the finger piece 17. To this end means are provided for at will locking or setting the frame or member 58 so that the locking tooth 69 is held out of action and the connecting devices comprising the pinions 55 and 52 are maintained in mesh with their coöperating gear wheels 38 and 35.

Such means comprise an arm 85 pivoted at 86 to an extension 58^a on the member 58, said arm extending forward and terminating in an off-set finger piece 87. At the rear 5 of its pivot the arm 85 terminates in a downwardly curving nose 88 which is engaged by the upper rear end of a leaf spring 89, said spring being riveted at 90 or otherwise secured to the rear of the ex- 10 tension 58^a. The lower edge of the arm 85 is provided near its forward end with a downwardly extending locking tooth 91 which is adapted to coöperate with a notch 92 cut in a rod 93 mounted on the end bars 15 of the platen carrier and corresponding to the usual paper finger rod of the machine. Normally, however, the spring 89 coöperates with the nose 88 to hold the locking tooth 91 up out of engagement with the 20 notch 92 as shown in Fig. 1. When it is desired to release the right-hand platen section from control of the locking device 69, the operator pushes rearward against the finger piece 87, thereby swinging the member 25 58 on its pivot so that the locking tooth 69 is disengaged from the gear wheel 35 and the gear wheels 38 and 35 are connected through the pinions 55 and 52. The parts at this time will be in the position shown 30 in full lines in Fig. 2. By depressing the finger piece 87 the spring 89 may be overcome and the tooth 91 may be caused to engage with the notch 92 as shown by dotted lines in said Fig. 2. This operation locks the 35 rocking member or frame 58 in the Fig. 2 position and it is obvious that as long as the locking devices 91 and 92 remain effective, the platen sections will at all times be connected and will receive simultaneously uniform extents of rotation or line space movements. When it may be desired again to make use of the platen sections separately 40 this may be done by pressing upward against the finger piece 87; the locking tooth 91 will be disengaged from the notch 92 and the spring 75 allowed to restore the member 58 to the Fig. 1 position. Of course, the manually operated locking device 91 may be employed if found desirable when 45 50 the changeable gears are set as in Fig. 4.

My present invention while particularly adapted for use in railroad waybilling work is, of course, not limited to such use but as has been stated it may be employed for 65 writing various other styles of commercial typewriting. The invention as described embodies a platen composed of separate rotary sections or divisions, two in number in the present instance, which may be regarded as separate platens providing for separately controlling different work sheets. By automatically coupling the platens or sections said sheets may be advanced together equal or different extents at a single 69 75 line spacing operation. The variation in

the extent of line spacing advance or movement is effected in the present case by varying or changing certain elements in a train of gears or coupling means, these changeable gears or elements being settable by hand to effect such variation. When not coupled together one of the platens or sections is locked and will remain quiescent when the other is turned. 70

Various changes may be made in said invention without departing from the spirit and scope thereof. 75

What I claim as new and desire to secure by Letters Patent, is:—

1. In a typewriting machine, the combination of two platens, line spacing means for one of the platens, means for automatically communicating line spacing movement to the other platen when said line spacing means are actuated, and means for varying the extent of said line spacing movement thus automatically communicated while the operation of said line spacing means remains constant. 80

2. In a typewriting machine, the combination of a divided platen, line spacing means for one of the sections of the platen, means for automatically communicating line spacing movement to another section of the platen, and means settable by hand for varying the extent of said line spacing movement thus automatically communicated while the operation of said line spacing means remains constant. 95

3. In a typewriting machine, the combination of two separate platens, means operating automatically to couple said platens together so that turning movement communicated to one platen will be communicated to the other platen, and means for varying certain of the elements of said coupling means. 100

4. In a typewriting machine, the combination of two separate platens, and means effective at a single operation for turning 110 said platens to the same extent, certain of the elements of said means being variable so that both said platens will be turned but to different extents at a single operation.

5. In a typewriting machine, the combination of a platen comprising a plurality of rotary sections, and means operative by a single finger piece for at will turning said sections simultaneously either to the same extent or to different extents. 115

6. In a typewriting machine, the combination of a two-part rotary platen, line spacing mechanism for turning one of said parts, means operative by said part as it is turned for transmitting a different extent 125 of turning motion to the other of said parts, and means for rendering said transmitting means inoperative to transmit motion to the second of said parts and for simultaneously locking said second part against rotation. 130

- 6
7. In a typewriting machine, the combination of two separate platens, a carriage on which said platens are mounted, means operating automatically to couple said platens together so that turning movement communicated to one platen will be communicated to the other platen, said coupling means operating automatically at a predetermined point in the travel of the carriage, and means for varying certain of the elements of said coupling means.
8. In a typewriting machine, the combination of two separate platens, a carriage on which said platens are mounted, means operating automatically to couple said platens together so that turning movement communicated to one platen will be communicated to the other platen, said coupling means operating automatically at a predetermined point in the travel of the carriage, and means for varying certain of the elements of said coupling means.
9. In a typewriting machine, the combination of a traveling carriage, two separate platens thereon, means operative by the traveling carriage to couple said platens together, and means for varying certain of the elements of said coupling means.
10. In a typewriting machine, the combination of two separate platens, means operating automatically to couple said platen together, said means including coupling devices mounted independently of said platens but operatively connectible with both platens, and means for at will varying certain of the elements of said coupling devices.
11. In a typewriting machine, the combination of a rotary platen comprising a plurality of sections, and gear connections for connecting said sections, said connections comprising changeable gears shiftable to vary the relative speed of said platen sections.
12. In a typewriting machine, the combination of a carriage, a platen comprising two coaxial rotary sections arranged end to end, paper feeding means associated with each section for feeding separate sheets over the different sections or a single wide sheet over both sections, and means for simultaneously turning both sections at different rates of speed in order to feed separate sheets different extents, said means being adjustable to turn both platen sections in unison to the same extent to feed a single wide sheet uniformly over both of said sections.
13. In a typewriting machine, the combination of two separate platens, line spacing devices, devices for holding one of said platens against rotation, means operating automatically to render said holding devices inoperative and to couple said platens together, and means for at will varying cer-
- tain of the elements of said last recited means to vary the effect of said line spacing devices on one of said platens.
14. In a typewriting machine, the combination of a platen, line spacing devices operative to turn the same, a second platen, a lock normally preventing the rotation of said second platen, means for unlocking said lock and connecting said second platen to be operated by said line spacing devices, and means for varying certain of the elements of said last named means to vary the effect of said line spacing devices on said second platen.
15. In a typewriting machine, the combination of a platen, a toothed wheel connected therewith, a second platen, a second toothed wheel connected with said second platen, means movable automatically into and out of engagement with said toothed wheels for coupling and uncoupling the same, and means for varying certain of the elements of said coupling means to vary the action of one wheel on the other.
16. In a typewriting machine, the combination of two separate platens, gear devices for connecting said platens to transmit the movement of one platen to the other, and gear changing means for shifting certain of said devices to cause the platens to move simultaneously together to the same extent or for at will causing the platens to move simultaneously differentially.
17. In a typewriting machine, the combination of two separate platens, gear devices for connecting said platens to transmit the movement of one platen to the other, gear changing means for shifting certain members included in said devices to cause the platens to move simultaneously together to the same extent or for at will causing the platens to move differentially at the same time, and means operating automatically to move certain members included in said gear devices into and out of operation to connect and disconnect the platens.
18. In a typewriting machine, the combination of a rotary platen comprising a plurality of sections, means for coupling said sections together to turn in the same direction but at different rates of speed, and means for rendering said coupling means inoperative so that one of said sections may be turned while another remains quiescent and for simultaneously locking said quiescent section positively against rotary movement.
19. In a typewriting machine, the combination of a sectional platen comprising two co-axial rotary sections arranged end to end, a line spacing ratchet wheel connected to one of said sections, a hand actuated pawl co-operative with said ratchet wheel, a gear wheel constantly connected with one of said sections, a pair of manu-

ally shiftable gear wheels of different diameters constantly connected with the other of said sections, a movable frame, connected pinions supported on said frame, and means for automatically moving said frame to throw said pinions into and out of connection with said gear wheels.

20. In a typewriting machine, the combination of two co-axial platens, a gear wheel connected to one platen, a pair of gear wheels connected to the other platen, a pinion coöperative with said first named gear wheel, a pair of pinions connected to the first named pinion and coöperative with said pair of gear wheels, and means for effecting a relative movement between said pair of gear wheels and said pair of pinions in a direction parallel with their axes to bring at will one or another of said pair of gear wheels into position to be engaged by their associate pinions.

21. In a typewriting machine, the combination of two co-axial platens, a gear wheel connected to one platen, a pair of gear wheels connected to the other platen, a pinion coöperative with said first named gear wheel, a pair of pinions coöperative with said pair of gear wheels, said pair of pinions and said first named pinion being connected, means for effecting relative shifting movement between said gear wheels and said pair of pinions in a direction parallel with their axes to bring at will one or another of said pair of gear wheels into position to be engaged by the associate one of said pair of pinions, a movable frame on which all of said pinions are mounted, and means operative automatically to move said frame and bring said pinions into coöperative relationship with said gear wheels, the relative shifting movement being effected independently of said automatically operating means.

22. In a typewriting machine, the combination of a carriage, a shaft supported thereon, two platens mounted end to end on said shaft, a pair of gear wheels connected to turn with said shaft and slidably mounted thereon, another gear wheel co-axial with said pair of gear wheels and connected to turn with one of said platens, the other of said platens being fixedly connected with said shaft, a pair of pinions adapted to mesh with said pair of gear wheels, another pinion adapted to mesh with said other gear wheel, said pair of gear wheels being shiftable by hand along said shaft to predetermined positions to bring them alternatively into register with the corresponding ones of said pair of pinions, and devices for retaining said pair of gear wheels in either of their predetermined positions.

23. In a typewriting machine, the combi-

nation of a two-part rotary platen, gears for connecting the parts of said platen, hand controlled means for moving said gears into mesh, and locking devices for maintaining said gears positively in operation.

24. In a typewriting machine, the combination of a two-part rotary platen; gear devices for connecting the parts of said platen; a movable frame on which certain of said gear devices are supported; and manual means for controlling said movable frame, said manual means comprising an arm pivoted to said movable frame and provided with a finger piece, and a spring for determining the normal position of said arm.

25. In a typewriting machine, the combination of a carriage; a two-part rotary platen; gear devices for connecting the parts of said platen; a movable frame on which certain of said gear devices are supported; manual means for controlling said movable frame, said manual means comprising an arm pivoted to said movable frame and provided with a finger piece, and a spring for determining the normal position of said arm; and locking devices for holding said frame in position to maintain the gear devices thereon in operation, said locking devices comprising a locking tooth on said arm and a coöperative locking device on the carriage.

26. In a typewriting machine, the combination of a two-part rotary platen, coupling devices for connecting the parts of said platen, automatic means for rendering said coupling devices effective, and hand controlled means also operative to render said coupling devices effective.

27. In a typewriting machine, the combination of a two-part rotary platen, coupling devices for connecting the parts of said platen, automatic means for rendering said coupling devices effective, hand controlled means also operative to render said coupling devices effective, and locking devices for maintaining said coupling devices in operation.

28. In a typewriting machine, the combination of a carriage, a two-part rotary platen, coupling devices for connecting the parts of said platen, said coupling devices being movable into and out of operative position, and hand controlled locking devices for maintaining said coupling devices in operative position in all positions of said carriage.

Signed at Syracuse, in the county of 120
Onondaga and State of New York, this 20th
day of February A. D. 1913.
